UNITED STATES PATENT OFFICE.

JOSEPH H. FLANIGAN, OF LEIGHTON, ALABAMA.

SLIDING-JAW WRENCH.

SPECIFICATION forming part of Letters Patent No. 660,421, dated October 23, 1900.

Application filed May 3, 1900. Serial No. 15,400. (No model.)

To all whom it may concern:

Be it known that I, JOSEPH H. FLANIGAN, a citizen of the United States, residing at Leighton, in the county of Colbert and State of Alabama, have invented certain new and useful Improvements in Sliding-Jaw Wrenches; and I do declare the following to be a full, clear, and exact description of the invention, such as will enable others skilled in the art to 10 which it appertains to make and use the same.

The invention relates to sliding-jaw wrenches.

The object of the invention is to improve the construction shown and described in Letters Patent No. 639,369, granted to me December 19, 1899, whereby I am enabled to secure an additional and finer adjustment.

With this object in view the invention consists in certain features of construction and 20 combination of parts which will be hereinafter fully set forth.

In the accompanying drawings, Figure 1 is a side elevation of the wrench, showing the movable jaw locked. Fig. 2 is a similar view 25 showing the movable jaw unlocked. Fig. 3 is a transverse section on line xx of Fig. 1. Fig. 4 is a transverse section on line yy of Fig. 2. Fig. 5 is a transverse sectional view on line zz of Fig. 1. Fig. 6 is a detail perspective view of the locking-cam for the 30 movable jaw. Fig. 7 is a longitudinal sectional view through the wrench, and Fig. 8 is a detail perspective view of the supplemental jaw.

Referring to the drawings, 1 designates the shank of the wrench, having at one end fixed jaws a and b and at the other end a handle 3. The jaw 4 is rigidly connected to and preferably formed integral with a sliding yoke or 40 collar 5 by arms 6.

7 denotes a locking-cam journaled between the jaw 4 and its yoke or collar 5 and is provided with teeth 8, which are adapted to engage corresponding teeth 9, formed on one of the sides of the shank 1, and lock the sliding jaw in its adjusted relation to the collar or yoke. The cam is provided with a fixed operating-handle 9, by means of which the teeth of the cam may be thrown into and out 45 of engagement with the teeth of the shank. The cam is held in either position by a spring 10.

The parts just described operate in substantially the same manner as the corresponding parts in the patent referred to, and a further 55 description is not thought to be necessary.

While a wrench thus constructed will meet the general demands of a mechanic, there are occasions when a fine adjustment of the jaws is desired, and, in fact, is necessary, and to 60 this end I have provided the sliding jaw with an auxiliary jaw c , designed to coact with the fixed jaw b . This jaw has a sliding engagement upon the jaw 4 and is actuated by a screw d , which in turn is actuated by a nut e . 65 After the jaw 4 has been bodily moved to secure the approximate adjustment and has been locked in place by the cam 7 the nut e is worked in the proper direction to advance the supplemental jaw c toward the jaw b , 70 thus securing a finer adjustment than could be obtained by the locking-cam.

For general purposes the jaws a and 4 of the wrench will answer; but where it is desired to get a fine adjustment the jaws b and 75 c will be found very effective.

From the foregoing description, taken in connection with the accompanying drawings, the construction, operation, and advantages of my improved sliding-jaw wrench will be 80 readily apparent without requiring an extended explanation. It will be seen that the device is simple of construction, that said construction permits of its manufacture at small cost, and that it is exceedingly well 85 adapted for the purpose for which it is designed.

Various changes in the form, proportion, and the minor details of construction may be resorted to without departing from the principle or sacrificing any of the advantages of 90 this invention.

Having thus fully described my invention, what I claim as new, and desire to secure by Letters Patent of the United States, is— 95

1. In a wrench, the combination, with a shank having two fixed jaws at its outer end, of a sliding jaw movable upon said shank and adapted to coact with one of the fixed jaws, means for locking the sliding jaw in 100 adjustment, a supplemental jaw carried by the sliding jaw and coöperating with the other fixed jaw, and means for adjusting said supplemental jaw independent of the sliding

5 jaw, said means also serving to lock the supplemental jaw in its advanced or retracted position of adjustment independent of the locking means of said sliding jaw, substantially as set forth.

10 2. In a wrench, the combination, with a shank having two fixed jaws at its outer end, of a sliding jaw movable upon said shank and adapted to coact with one of the fixed jaws, means for locking the sliding jaw in adjustment, a supplemental jaw carried by the sliding jaw and coöperating with the other fixed jaw, a screw applied to the supplemental jaw, and a nut upon the screw for 15 adjusting said jaw independent of the sliding jaw and serving to hold said supplemental jaw in its advanced or retracted position of adjustment independent of the locking means of the sliding jaw, substantially as set forth.

20 3. In a wrench, the combination with a

shank having two fixed jaws at its outer end, of a yoke or collar slidably mounted on the shank and carrying at one side a main jaw coöperating with one of said fixed jaws, means for locking the yoke and main jaw in adjusted position, a supplemental jaw slidably mounted upon the inner face of the main jaw on the opposite side of the yoke and coöperating with the other fixed jaw, a screw mounted in the yoke and carrying the supplemental jaw, and an adjusting nut on said screw, substantially as set forth.

25 In testimony whereof I have hereunto set my hand in presence of two subscribing witnesses.

JOSEPH H. FLANIGAN.
